UNITED STATES PATENT OFFICE.

WILLIAM C. HUEBNER, OF BUFFALO, NEW YORK, ASSIGNOR TO HUEBNER-BLEISTEIN PATENTS COMPANY, OF BUFFALO, NEW YORK.

ADJUSTMENT-INDICATING MEANS FOR PHOTOGRAPHIC-PRINTING APPARATUS AND OTHER APPARATUS.

Application filed May 9, 1921. Serial No. 467,957.

To all whom it may concern:

Be it known that I, WILLIAM C. HUEBNER, a citizen of the United States, residing at Buffalo, in the county of Erie and State of New York, have invented a new and useful Improvement in Adjustment-Indicating Means for Photographic-Printing Apparatus and Other Apparatus, of which the following is a specification.

10 This invention relates more particularly to adjustment indicating means for photographic printing or composing apparatus of the kind disclosed in my application for patent, Serial No. 248,623 filed Aug. 6, 1918, 15 of which the present application is a division.

These apparatus are adapted for producing photographically upon the sensitized press plate any desired number of like or 20 different prints in any desired position or relative arrangement. For instance, the apparatus are adapted for repeating prints from the same transparent printing plate or negative in a desired arrangement on a single 25 sensitized press plate which is afterwards used for printing a plurality of impressions, and also for composing purposes where it is desired to place different subjects in a pre-determined arrangement on the press plate. 30 The apparatus are also adapted for making press plates for multi-color printing where it is necessary to photograph the prints in exact register on different sensitized plates that are used for printing the different 35 colors.

Such apparatus comprise a support for the sensitized press plate, a light chamber or support arranged to support a transparent photographic negative or printing plate, 40 hereinafter called the "printing plate," in front of the sensitized surface of the press plate, a back support or pressure device for the sensitized plate for insuring a tight uniform contact of the sensitized surface with the printing plate, means for causing the 45 passage of light through the printing plate for photographing the print on the sensitized plate, and means for effecting a relative movement between the sensitized plate and the printing plate parallel with the sensitized surface to enable the prints to be 50 made in desired predetermined and registered locations and positions on the sensitized plate.

The object of the invention is to provide 55 means, whereby the adjustments of the adjustable member of such apparatus, or analogous adjustable members are indicated with microscopic precision and can be quickly and easily ascertained or visually 60 observed so as to enable required very fine adjustments to be made rapidly with extreme precision.

In the accompanying drawings:

Fig. 1 is a fragmentary side elevation of 65 a photographic printing machine embodying the invention.

Fig. 2 is a plan view thereof.

Fig. 3 is an end elevation thereof with the light chamber removed. 70

Fig. 4 is a fragmentary transverse elevation, partly in section, of the auxiliary carriage.

The sensitized press plate D is supported in a plane parallel with the face of the 75 printing plate B in a plate holder E which is mounted on a carrying frame F arranged to move vertically parallel with the plane of the sensitized plate. This carrying frame is mounted on a second frame or auxiliary 80 carriage G which, in turn, is adjustable horizontally parallel with the plane of the sensitized plate on a main carriage H which is movable on the base 20 of the machine toward and from the support for the printing 85 plate. This main carriage H as shown extends horizontally transversely of the machine over the stationary base 20 and is provided at each of its opposite ends with a pair of supporting rollers 57 arranged to 90 roll on longitudinal rails 58 on the base 20 at opposite sides thereof. 59 represents rails secured on the base 20 and overhanging the rollers 57 to prevent the tilting or lifting of the carriage off of the supporting rails. 95 The carriage H is also preferably provided between its ends with front and rear pairs of rollers 60 adapted to roll on tracks 60^a on top of the base 20 for preventing the sagging or deflection of the middle portion of 100 the carriage. The carriage is caused to travel accurately in a straight line by a guide bar 61, Fig. 3, on the carriage extending between a fixed face 62 and an adjustable gib or bar 62^a on the carriage. 105

The auxiliary carriage G is provided with supporting rollers 63 arranged to roll on transverse rails 63^a on the main carriage

and the main carriage is provided with rails 64 which overhang the rollers 63 to prevent the lifting or tilting of the auxiliary carriage. 65. Fig. 1, represents a rib on the main carriage cooperating with a fixed rib 65 and an adjustable gib or bar 65 on the auxiliary carriage for accurately guiding the latter carriage. The auxiliary carriage G is provided at its opposite ends with parallel upright posts 66 which are preferably tubular and are rigidly connected at their tops by a cross head 67. The vertically adjustable carrying frame F consists of horizontal top and bottom bars 68 rigidly connected by vertical end bars 69. This frame is slidably mounted by bearings 69 on the tubular upright posts 66 of the auxiliary carriage. The carrying frame is supported and adjusted vertically by two upright screw shafts 72 which are suitably journaled on the auxiliary carriage G and have screw-threaded engagements with nuts or sleeves 73 secured on the carrying frame. These screw shafts are connected at their lower ends by spiral gears 74, 75, to an adjusting shaft 76 which is journaled on and extends horizontally transversely of the machine on the auxiliary carriage G.

Any suitable means may be employed for adjusting the carrying frame F and auxiliary carriage G respectively vertically and horizontally for placing any desired portion of the sensitized plate D opposite the printing plate. For adjusting the carrying frame, the shaft 76 is shown as being connected by bevel pinions 85 to an upright shaft 86, Fig. 4, journaled on the auxiliary carriage. This shaft is connected by bevel gears 87 to an operating shaft 88 which can be turned by a crank 89 applied to its outer end or by other suitable means. The carrying frame can be moved quickly to an approximate position by turning this crank. In order to facilitate a fine, accurate adjustment of the carrying frame, a fine adjusting shaft 90 turned by a handle or wheel 91 is provided. A worm 92 on this shaft is adapted to mesh with a spiral gear 93 on the coarse adjusting shaft 88. The fine adjusting shaft 90 is journaled eccentrically in a bushing 94 which is adapted to be turned by a handle 95 in a bearing 96 on the auxiliary carriage for throwing the fine adjusting worm into and out of mesh with the coarse adjusting shaft. After the carrying frame has been adjusted coarsely to an approximate position by turning the handle 89, the fine adjusting worm is placed in connection with the coarse adjusting shaft and turned to give the desired accurate adjustment of the carrying frame.

The adjusting means shown for the auxiliary carriage G comprise a toothed rack 97 on one side of the carriage which meshes with a spiral gear 98 on an inclined

shaft 99 suitably journaled on the main carriage H. This inclined shaft is connected by spiral gears 100 to a coarse adjusting shaft 101 which is provided at its outer end with a crank or handle 102 for turning it. 103 is a fine adjusting shaft for the auxiliary carriage. This shaft is provided with a worm adapted to be thrown into and out of mesh with a gear on the coarse adjusting shaft in the manner above explained in connection with the fine adjusting shaft for the carrying frame.

The adjustment of the auxiliary carriage is preferably shown by a suitable graduated scale 104, Fig. 1, fixed directly on the auxiliary carriage. This scale in the movement of the carriage, moves beneath a microscope 105 which is fixed on the main carriage above the scale 104. This microscope projects an enlarged image of the underlying graduations of the scale 104 on to a ground glass or screen 106, Fig. 2, disposed above the microscope. 107, Fig. 1, indicates a small electric lamp for illuminating the scale 104 which is preferably made of glass or other suitable transparent material. By the use of the microscope arranged in this way the scale 104 can be graduated into extremely fine fractions of an inch or unit of measure and the enlarged image of these fine graduations can be readily seen and read on the screen without requiring the operator to place his eye close to the microscope as would have to be done in the case of the use of an ordinary microscope. The screen 106 furthermore is also preferably provided with a fixed graduated scale which enables a still finer subdivision of the fine divisions of the scale 104. Since the scale 104 is fixed to and moves with the auxiliary carriage and is read by the microscope and screen which are mounted on a relatively fixed part, there is no possibility of error due to lost motion between the moving and the designating part of the indicating device and it is therefore possible to readily adjust the auxiliary carriage accurately to positions measured in thousandths of an inch or less.

The adjustment of the carrying frame F is indicated in a similar manner by a scale 108, Fig. 1, secured directly on the carrying frame and adapted to be read by the microscopic projection device 109, similar to that above explained.

The adjustment indicating means for showing with precision the adjustments of the adjustable members are illustrated and described in this application just as they are disclosed in my said application Serial No. 348,623, but manifestly the indicating means are not restricted to use in machines of that particular construction and it is not intended to so restrict this invention. The invention is equally applicable to apparatus

of other construction having an adjustable part or member, for the purpose of showing with precision the adjustments of such part or member. Furthermore the invention is not limited to the particular construction of the indicating means herein shown and described.

I claim as my invention:

1. In a photographic printing apparatus, 10 the combination with an adjustable member, of a graduated scale and a microscope, one of which devices moves with said adjustable member past said other device, and a screen in fixed relation to said microscope on which 15 said microscope projects an enlarged image of the portion of said scale opposite the microscope.
2. In a photographic printing apparatus, 20 the combination of an adjustable member, a graduated scale fixed on said adjustable member, a microscope past which said scale moves, and a screen on which said microscope projects an enlarged image of a portion of said scale.
3. In a photographic printing apparatus, 25 the combination with an adjustable member, of a graduated scale, and a microscope, one of which is fixed on said adjustable member and moves past said other device, and a screen in fixed relation to said microscope on which 30 said microscope projects an enlarged image of the portion of said scale opposite the microscope, said screen having a part cooperating with the scale image to indicate the adjustment of said adjustable member.
4. In a photographic printing apparatus, 35 the combination with an adjustable member, of a graduated scale and a microscope, one of which devices moves with said adjustable member past said other device, and a screen in fixed relation to said microscope on which 40 said microscope projects an enlarged image of the portion of said scale opposite the microscope and which is graduated to indicate 45 subdivisions of the projected scale graduations.
5. In a photographic printing apparatus, 50 the combination with an adjustable member, of a graduated scale and a microscope, one of which devices partakes in the adjustments 55 of said adjustable member and moves past said other device, and a screen in fixed relation to the microscope on which an enlarged image of the portion of said scale opposite

the microscope is projected by said microscope.

6. In a photographic printing apparatus, 60 the combination of an adjustable member, a graduated scale arranged to partake in the adjustments of said adjustable member, a stationarily mounted microscope past which 65 said scale moves, and a screen on which said microscope projects an enlarged image of the portion of the scale opposite the microscope.

7. In a photographic printing apparatus, 70 the combination of an adjustable member, a graduated scale arranged to partake in the adjustments of said adjustable member, a stationarily mounted microscope past which 75 said scale moves, and means cooperating with said microscope to display an enlarged image of the portion of said scale opposite the microscope, said means having graduations to show subdivisions of the projected scale graduations.

8. The combination with an adjustable member, of a minutely graduated scale for 80 indicating adjustments of said member, and a microscope associated with said scale and one of which devices is movable relatively to the other for projecting enlarged images of successive portions of said scale, and means in fixed relation to said microscope cooperating with said microscope to display 85 said enlarged images.

9. The combination with an adjustable member, of a minutely graduated scale which partakes in the adjustments of said 90 adjustable member, a microscope associated with said scale and past which the scale moves for projecting enlarged images of successive portions of said scale, and means cooperating with said microscope to display 95 said enlarged images.

10. The combination with an adjustable member and means for effecting minute 100 adjustments of said member, of a minutely graduated scale for indicating adjustments of said member, and a microscope associated 105 with said scale and one of which devices is movable relatively to the other for projecting enlarged images of successive portions of said scale, and means in fixed relation to said microscope cooperating with said microscope to display said enlarged images.

WILLIAM C. HUEBNER.
